INVENTOR

UNITED STATES PATENT OFFICE.

JAMES WALTER CATTY, OF NEW YORK, N. Y.

DESIGN FOR A DOILY.

SPECIFICATION forming part of Design No. 32,414, dated March 27, 1900.

Application filed February 16, 1900. Serial No. 5,541. Term of patent 7 years.

To all whom it may concern:

Be it known that I, JAMES WALTER CATTY, a subject of Her Majesty the Queen of Great Britain, residing in the city of New York, borough of Brooklyn, in the State of New York, have invented and produced a new and original Design for a Doily or Similar Article, of which the following is a specification, reference being had to the accompanying drawing, forming part thereof.

The figure is a plan view of a square piece of paper or cardboard, showing my new design of a doily or similar article.

As shown in the drawing, the leading or material feature of my design consists of a line of perforated dots A a short distance from each side of the edge of a square of paper or cardboard, each line equally distant from the edge of the paper or cardboard and intersecting each other near the four corners.

Under these at each of the four corners are

two sprigs of oak-leaves and acorns embossed on the doily, which are arranged parallel with the edges of the paper or cardboard, their stalks intersecting each other at C and being tied together with a bow.

In the center of the doily or similar article is embossed a colonial wreath D of oak-leaves and acorns tied at the base E with a bow with long streaming ends, as shown in the drawing.

Having described my invention, what I claim as new, and desire to secure by Letters Patent, is--

The design for a doily or similar article, as herein shown and described.

In testimony whereof I have signed my name to this specification in the presence of two subscribing witnesses.

JAMES WALTER CATTY.

Witnesses:

MADGE A. DILLON,
H. CAMPBELL McLAREN.
